UNITED STATES PATENT OFFICE.

THOMAS S. HUNTINGTON, OF NEW YORK, N. Y., ASSIGNOR TO THE GOLD MEDAL MACHINE COMPANY, OF ORANGE, MASSACHUSETTS.

SEWING-MACHINE.

SPECIFICATION forming part of Letters Patent No. 247,357, dated September 20, 1881.

Application filed March 5, 1881. (Model.)

To all whom it may concern:

Be it known that I, THOMAS S. HUNTINGTON, of New York, county and State of New York, have invented Improvements in Sewing-Machines, of which the following description, in connection with the accompanying drawings, is a specification.

This invention relates to improvements in sewing-machines of that class wherein the shuttle oscillates in the arc of a circle about a horizontal axis, the shuttle deriving its motion from a rock-shaft.

My improvements relate to means for operating the shuttle-carrying rock-shaft, whereby all tendency of the oscillating shuttle to move beyond its established points in each direction is overcome, notwithstanding variations in speed.

It is well known that oscillating shuttles actuated from rock-shafts have their throw or movement in each direction increased with each increase of speed, and in running such a machine at high speed (it at slow speed working properly) there is such an increase of movement of the shuttle, owing chiefly to momentum, as to break the shuttle-thread and seriously affect the stitch by pulling from the shuttle at high speed more thread than is drawn from the shuttle at the average or slow speed of the machine—the speed at which the machine is for the most part worked. This additional slack in the shuttle-thread destroys the uniform appearance of the stitch. To obviate the difficulties arising from the overthrow of the shuttle, the thread has been delivered from the shuttle near the center of its oscillation, the delivery of the shuttle-thread out of center being just sufficient to allow slack thread, just as the feed takes place; but as the material increases in thickness or the stitch in length, the amount of slack thread provided for by the delivery of the shuttle-thread a little out of the center of oscillation of the shuttle is so small as to be inadequate and breaks the shuttle-thread or puckers the goods. These same difficulties are also produced by overthrow.

In my improved machine I employ a sliding pin on a connecting-rod, which pin, before entering the slot in the crank-arm of the oscil-

lating shuttle-moving rock-shaft, is extended through a slot of a guide-block, the latter so controlling the movement of the said pin as to cause it to move the said crank and rock-shaft only a certain predetermined distance, no matter at what speed the machine is run, thus completely obviating all evil effects from overthrow. The slot in this guide-block is made more or less irregular or out of line with relation to the axis of the said rock-shaft, to cause the said pin to approach toward or recede from the axis of the said rock-shaft in the slot of the said crank and vary the velocity of the shuttle at certain portions of its travel—as, for instance, to move it rather slowly until the point of the shuttle enters the loop of needle-thread, when the speed of the shuttle is gradually increased until the shuttle passes through the loop, but is again moved slowly as it comes to its most forward position, where it rests while the take-up, which commenced to rise before the shuttle finished its passage through the loop, completes its rise, operates and finishes the stitch just made, the shuttle completing its forward movement just as the take-up finishes its upward movement, the needle-bar being also at its highest throw.

By giving to the shuttle an irregular movement I am enabled to actuate the needle-bar at a uniform rate of movement, and thus obviate the use of a heart-cam or the so-called "dip motion" of the needle-bar to make slack in the needle-thread for the passage of the shuttle.

My shuttle is arranged to oscillate within an annular chamber, and is supported upon a shuttle-rest hinged to a plate or disk connected with the shuttle-actuating rock-shaft, the said rest having connected with it a shuttle-holder, which holds the shuttle pressed up against the said plate or disk.

The take-up is composed of a sector or arm having an irregular slot, and pivoted at one side of the center of the needle-bar-moving shaft. The sector derives its movement from the rotating crank-pin which moves the needle-bar, the crank-pin entering a straight slot in a block at right angles to the needle-bar. This sector, owing to the location of its pivot and the shape of its slot, has given to it a va-

riable motion, the sector moving slowest as the crank-pin descends to pass its lower center, the speed of the sector gradually increasing as the said crank-pin rises from its lower to its highest center. The teeth of the sector, in the arc of a circle, engage a pinion attached to a shaft having adjustably secured to it the take-up arm, the latter thus having given to it motion in the arc of a circle of greater or less radius.

Figure 1 is a side elevation of a sewing-machine containing my improvements, the framework being partially broken away; Fig. 2, an under-side view thereof, the feeding mechanism being omitted; Fig. 3, a partial cross-section and front view of the head, with the face-plate of the head removed to show the take-up-moving devices, the needle-bar being partially broken out. Fig. 4 is a detail of the guide-block, the forked crank or arm at the end of the oscillating shuttle-moving shaft, and the sliding pin; and Fig. 5, an inner-side view of the needle-bar.

The frame-work *a* of the machine, the main rotating shaft *a'*, crank-pin *a''*, the vertical shaft *a³*, the gears *a⁴* *a⁵*, and the counterbalanced crank *a⁶* at its lower end, are, as herein shown, all as in the Singer sewing-machine, and need not, therefore, be particularly described.

The feeding devices, omitted from the drawings because not of my invention, may be as in the Singer family machine or as in the New Home machine.

The balanced crank *a⁶*, as herein shown, is provided with a pin, *b*, which enters a slot, *b'*, in a radius-bar, *b²*, pivoted to the under side of the frame or bed of the machine at *b³*. This radius-bar at its front end has joined with it the connecting-rod *c*, having at its forward end a pin, *d*, which I shall hereinafter denominate the "sliding pin." This pin is extended through the slot *e* in the guide-block *e'*, herein shown as fixed to the under side of the frame or bed of the machine. The outer end of this pin is made to enter a slot in the crank-arm *f*, secured to the horizontal rock-shaft *f'*, supported in suitable bearings, and having at its other end the arm or disk *f²*, against which the inner side of the shuttle *g* is kept pressed by the holder *g'*, secured to the shuttle-rest *g²*, pivoted or hinged to the said arm or disk *f²* at 2. The forward part of the connecting-rod *c* is acted upon at its outer side by a ledge, *c²*, which serves to keep the pin *d* pressed into the slot in the crank *f*. The slot *e* in this guide-block, shaped as shown in Fig. 4, is curved irregularly with relation to the center of the rock-shaft *f'*, (denoted in dotted lines in the said figure,) and the sliding pin *d*, owing to the shape of the said slot *e*, is made to approach toward and recede from the center of the said rock-shaft in the groove of the said arm *f*, as the sliding pin is moved by the connecting-rod *c*, thus accelerating and lessening the speed of the shuttle during portions of each stroke, to cause it to move up to and catch the loop of nee-

dle-thread slowly and thereafter move faster while passing through the said loop, and then continuing its forward movement more slowly, and finally almost stopping near its extreme forward position for the take-up to finish the stitch. This sliding pin, loosely connected with the crank-arm *f*, and guided in this way by the slot *e* of the guide-block *e'*, always operates the said crank-arm and rock-shaft for just the same distance at each forward movement of the sliding pin, and causes it to carry the point of the shuttle forward to just the same point at whatever speed the shaft *a'* of the machine may be run, thus completely obviating all difficulty arising from overthrow of the shuttle and improper strain on the shuttle-thread, as before explained.

The holder and rest are held up in operative position by a rest-locking device, *h*, shown as a turn-button.

The shuttle *g* contains a disk-bobbin of usual construction, loosely placed in a recess from the inner side of the shuttle, and the thread *h* is drawn from the said bobbin out through proper thread-leading holes made in the upper or outer edge of the shuttle-body, any usual tension spring or device being employed to produce a uniform tension on the shuttle-thread. The shuttle on its back-stroke gives up slack thread for the feed, substantially as do the usual reciprocating straight shuttles in the machines hereinbefore referred to. This shuttle is made to oscillate in a circular cavity; but it may be readily removed therefrom by turning the shuttle-rest out from the said cavity, and the shuttle may, if desired, be removed and its tension altered without breaking the shuttle-thread or disturbing the material under the presser-foot.

The crank pin *a''*, carried by the usual disk at the end of shaft *a'* and provided with the usual friction-roller, is extended through the irregular slot *i* in the arm or sector *k*, pivoted at *k'* at one side the center of shaft *a'*. The teeth 3 of this sector engage the teeth of the pinion *k²* on the short shaft or stud *k³*, having adjustably attached to it the take-up *k⁴*, it having at its end a hole or eye, *4*, to receive the needle-thread extended from the usual needle-thread tension device *l* under the loop *l'*, Fig. 3, and up through the stationary eye *l²*, Fig. 1, the needle-thread led through the said eye *4* being then led back through the eye *l²* into and through the eye *5* at the lower end of the needle-bar on the needle-fastening screw through the eye of the usual needle from its front side. Just after the needle-bar begins to descend the take-up commences to descend in the arc of a circle, and continues to so move until its lower end passes beyond the eye *l²*. During this time the shuttle enters and passes about half-way through the loop of needle-thread, when the shuttle, to move farther forward and not break the needle-thread, demands more thread from the needle and take-up. The needle-thread so demanded is quickly

supplied by the take-up, which is then moved back, giving up a little slack thread, which enables the largest part of the shuttle to pass through the loop of needle-thread, and as the shuttle completes the latter part of its passage through the said loop the take-up rises and accelerates the passage of the loop of needle-thread from the heel of the shuttle and takes up the slack in the needle-thread. The needle-bar is substantially at its highest point when the heel of the shuttle passes through the loop of needle-thread, and at such time the take-up commences to rise rapidly to take up the slack thread, and completes its upward motion just before the needle starts down.

The pivot of the take-up sector is located at one side the center of the shaft carrying the crank-pin which moves the said sector, and the slot in the sector is of such shape, in connection with the position of its pivot, that the crank-pin moves the take-up faster when the needle-bar rises than when it descends, thus giving all the time possible for the shuttle to get through the loop of needle-thread, and the time is different than were the pinion of the take-up driven from the needle-bar or at its speed. The crank-pin a^2 , after passing through the slot in the sector, enters a straight slot, m^2 , in a block, m , secured to the needle-bar m' . I do not desire to limit my invention to the exact devices shown for reciprocating the connecting-rod e from the rotating shaft of the machine, as I may employ for such purpose any other well-known mechanism employed in shuttle sewing-machines to reciprocate a horizontal rod lengthwise of the cloth-supporting bed. I do not broadly claim an oscillating take-up operated by a rack and pinion moving in unison with the needle-bar, as I am aware that that kind of a take-up is old.

I claim—

1. In a sewing-machine employing an eye-pointed needle, an oscillating shuttle, a rest, and rock-shaft provided with an arm or crank,

combined with connecting-rod and sliding pin 45 loosely connected with the said arm or crank, and a slotted guide-block to direct the said pin, substantially as and for the purpose described.

2. The reciprocating connecting-rod and its attached sliding pin, combined with the guide-block provided with an irregular slot, e , through which the said pin is extended, and with the arm of a shuttle-moving rock-shaft, with which the said pin is loosely connected, whereby the sliding pin is caused to approach toward and recede from the center of the said rock-shaft at each movement of the rock-shaft in each direction to vary the speed of the shuttle, substantially as described.

3. The reciprocating rod e and its sliding 60 pin, combined with the slotted guide-block, and the ledge to act upon one side of the connecting-rod and retain the said pin in the slot of the said block, substantially as described.

4. The sector pivoted as described, and 65 crank-pin to move it at a variable speed, combined with the take-up and pinion secured to the shaft of the take-up and operated by the sector, substantially as described.

5. In a sewing-machine, a needle-bar and eye-pointed needle having a uniform ascending and descending movement, combined with a take-up having a variable movement in its ascent and descent, and with the shuttle-carrier, and the semicircular shuttle g , adapted to oscillate, as described, about its own center, and with means to operate the carrier and shuttle at a variable speed at each forward and backward movement and prevent overrunning of the shuttle, substantially as described.

In testimony whereof I have signed my name to this specification in the presence of two subscribing witnesses.

THOMAS S. HUNTINGTON.
